UNITED STATES PATENT OFFICE.

CHARLES H. LITTLE, OF PIQUA, OHIO.

UNDERGARMENT.

No. 894,840.

Specification of Letters Patent.

Patented Aug. 4, 1908.

Application filed July 15, 1907. Serial No. 389,846.

To all whom it may concern:

Be it known that I, CHARLES H. LITTLE, a citizen of the United States, residing at Piqua, in the county of Miami and State of Ohio, have invented certain new and useful Improvements in Undergarments, of which the following is a specification.

Union or combination suits of underwear consisting of vests and pants as generally constructed in the seat, result in more or less inconvenience, annoyance, and discomfort to the wearer because of the tendency of the meeting or overlapping portions at the crotch to wrinkle, roll and form welts or spread and catch upon the buttocks, thereby requiring frequent readjustment.

This invention has for its object to overcome the objectionable features above enumerated and to provide a union suit which will require no adjustment in sitting, stooping, or squatting, or in assuming an erect attitude from either of these positions; to provide a suit which will not draw, roll or wrinkle in the seat while standing or sitting, and to provide a suit which will not draw on the buttock or inside the leg and thereby avoid friction and galling, and finally, to supply a suit of the character aforesaid which will be smooth, strong and reinforced in the seat.

The invention consists of a reinforcement of peculiar construction and arrangement stitched to the seat and extending over the overlapping edge portions bordering upon the crotch or opening and which acts to prevent the edge portions of the garment at the crotch especially from chafing or catching upon the buttocks or inner sides of the legs.

The invention further consists of the novel features which will be more particularly set forth, claimed and illustrated in the accompanying drawings forming a part of the specifications, and in which:

Figure 1 is a rear view of a combination under-garment of the union suit type, embodying the invention. Fig. 2 is a sectional view showing the seat from the inner side and bringing out more clearly the details. Fig. 3 is a front view of said garment, the lower portions of the legs being broken away.

Corresponding and like parts are referred to in the following description and indicated in all the views of the drawings by the same reference characters.

The reinforcement or protector 1 is approximately of triangular form with the apex omitted and is arranged upon the inner side

of the seat portion of the garment so as to extend over the overlapped edge portions bordering upon the opening in the seat. The suit opens in the front, said opening extending from the neck to the crotch and a short distance from the crotch upward in the rear to about the waist line, the seat portion having overlapped parts 2 which are designed to cover the buttocks and prevent exposure thereof. The reinforcement 1 has its opposite edges 3 converged, its top edge 4 upwardly curved and its lower edge 5 transversely curved and paralleling the upper curved edge 4 so that the points 6 may extend downward a short distance along the upper portion of the leg members. The overlapped edge portions 2 are upwardly converged in the rear of the seat portion, and terminate about at the waist line which is strengthened by a horizontal line of stitching 7. The upwardly converged edges 3 of the reinforcement are stitched to the garment along the upwardly converged edge portions of the overlapped parts 2. The upper curved edge 4 of the reinforcement is stitched to the garment and through the overlapped portions 2 thereof, the lower curved edge 5 of said reinforcement being loose. In the garment illustrated, the overlapped parts 2 form sections or gussets arranged between the leg members and form the seat, thereby providing ample fullness besides strengthening the same in addition to the reinforcement 1.

It will be understood that the reinforcement 1 extending over the opening formed between the overlapped portions of the seat, prevent separation or spreading of said overlapped parts and insure covering of the buttocks and prevent the formation of the edge portions of the parts 2 into rolls or welts or the catching of same around the buttocks or the rubbing thereof against the inner sides of the legs. The reinforcement 1 is preferably of the same material employed in the manufacture of the garment, being of knit fabric, hence insures a close fit besides preventing the discomfort of garments of this type constructed of non-stretchable material and requiring ample fullness to allow for freedom of movement of the body and limbs.

Having thus described the invention, what is claimed as new is:

1. An under-garment of the type comprising a vest and pants formed in one and open from the neck down the front and around the crotch and seat, and having edge portions of

- the seat overlapped, a reinforcement arranged upon the inner side of the seat opposite the overlapped edge portions thereof and having its end portions extended beyond said 5 overlapped edge portions and terminating in upwardly converged edges which are stitched to the respective overlapped portions of the seat equi-distant from and about parallel with their edges, said reinforcement having 10 its top and bottom edges parallel and upwardly curved, the upper edge being stitched transversely through the overlapped edge portions of the seat and the lower edge being loose.
- 15 2. A combination under-garment comprising vest and pants formed in one, and opening from the neck down the front and around the crotch and seat and having edge portions bordering upon the seat overlapped and up- 20 wardly converged, a reinforcement arranged

upon the inner side of the seat and covering the overlapped edge portions thereof, and having its top and bottom edges upwardly curved and its opposite edges upwardly converged 25 and stitched at its upper edge and at its opposite converged edges to the seat, the top stitching extending through the overlapped portions of the seat, and the converged stitching at opposite edges of said reinforcement being arranged some distance from the respective edges of the overlapped seat portions and extending approximately parallel therewith.

In testimony whereof I affix my signature in presence of two witnesses.

CHARLES H. LITTLE. [L. S.]
